UNITED STATES PATENT OFFICE.

WILLIAM P. M. BRAUN, OF PHILADELPHIA, PENNSYLVANIA.

DESIGN FOR A CAP FOR FILTERS.

SPECIFICATION forming part of Design No. 28,267, dated February 8, 1898.

Application filed December 28, 1897. Serial No. 664,124. Term of patent 7 years.

To all whom it may concern:

Be it known that I, WILLIAM P. M. BRAUN, of the city and county of Philadelphia, State of Pennsylvania, have invented a new and 5 original Design for Caps for Filters, of which the following is a specification.

My new design for the caps of filters is illustrated in the accompanying drawings, in which—

- o Figure 1 is a side elevation of a filter-cap embodying the design. Fig. 2 is a vertical sectional view of the same on the line $x x$ of Fig. 1, and Fig. 3 is a top plan view.

The design resides in the shape or conformation of the cap; and it consists, essentially, of a more or less flat extended top having a depending tubular portion projecting centrally therefrom and a tubular passage-way extending radially through the top.

In the drawings, A is the more or less extended flat top having a central boss a , from which extends the tubular portion B, and C is the tubular passage-way extending radially from the center through the body of the top A. 20

Having now described my design, what I claim as new, and desire to secure by Letters Patent, is as follows: 25

A cap for a filter substantially as herein described and shown. 30

In testimony of which invention I hereunto set my hand.

WILLIAM P. M. BRAUN.
